Mar. 21, 2019—(EP) Examination Report—App. 16713717.3.

(Continued)

(73) Assignee: **Citrix Systems, Inc.**, Fort Lauderdale, FL (US)

Primary Examiner — Daniel J Domino

(***) Term: **15 Years**

(74) Attorney, Agent, or Firm — Banner & Witcoff, Ltd.

(21) Appl. No.: **29/678,459**

CLAIM

(22) Filed: **Jan. 29, 2019**

The ornamental design for a display screen or portion thereof with transitional graphical user interface, as shown and described.

Related U.S. Application Data

DESCRIPTION

(63) Continuation of application No. 16/164,258, filed on Oct. 18, 2018, now Pat. No. 10,673,845, which is a (Continued)

FIG. 1 is the first image in a sequence for a display screen or portion thereof with transitional graphical user interface showing our new design;

(51) **LOC (13) Cl.** **14-04**

FIG. 2 is the second image thereof;

(52) **U.S. Cl.**

FIG. 3 is the third image thereof;

USPC **D14/485**

FIG. 4 is the design of FIG. 1 shown in an illustrative environment;

(58) **Field of Classification Search**

FIG. 5 is the design of FIG. 2 shown in an illustrative environment; and,

USPC **D14/485-495**

FIG. 6 is the design of FIG. 3 shown in an illustrative environment.

(Continued)

(56) References Cited

The appearance of the graphical user interface transitions sequentially between the images shown in FIGS. 1-3, and FIGS. 4-6 respectively.

U.S. PATENT DOCUMENTS

D104,443 S 5/1937 Elkonin
 7,111,323 B1 9/2006 Bhatia et al.

(Continued)

The process or period in which one image transitions to another forms no part of the claimed design. The difference in shading indicates a contrast of appearance and does not depict any particular color, texture, or material. The broken lines depicting the display screen, remainder of the graphical user interface, and illustrative environment show features that form no part of the claimed design.
